UNITED STATES PATENT OFFICE.

WILLIAM H. WILSON, OF NEW YORK, N. Y.

EYEGLASS-GUARD.

SPECIFICATION forming part of Letters Patent No. 761,619, dated May 31, 1904.

Application filed October 21, 1903. Serial No. 177,835. (No model.)

To all whom it may concern:

Be it known that I, WILLIAM H. WILSON, a citizen of the United States, and a resident of the city of New York, borough of Manhattan, in the county and State of New York, have invented a new and Improved Eyeglass-Guard, of which the following is a full, clear, and exact description.

The object of this invention is to provide superior means for attaching a soft cushioning material to eyeglass-guards. I have found that the best material for this purpose is a soft skin, such as chamois, and my invention lies in the peculiar manner of fastening this skin to the guard. With this end in view I first secure by riveting or other analogous means a section of relatively stiff and tough skin, such as ordinary leather, to the middle part of the guard, and then I fasten the chamois-skin to the leather by glue, cement, or the like. This provides a soft and durable guard and one which is much easier on the wearer than the cork and tortoise-shell guards now commonly employed, for the chamois-skin has a peculiar tendency to stick or adhere to the skin of the wearer, and owing to this the eyeglass equipped with my invention will be securely held in place by less pressure than that ordinarily employed.

This specification is an exact description of one example of my invention, while the claim defines the actual scope thereof.

Reference is to be had to the accompanying drawings, forming a part of this specification, in which similar characters of reference indicate corresponding parts in both views.

Figure 1 is a fragmentary perspective view showing my invention, and Fig. 2 is a section of the guard.

a indicates the metal section of the guard, which may of course be of any form and con-

struction desired. *b* indicates the section of leather, which is fastened by rivets *c* to the metal guard *a*, and *d* indicates the chamois-skin covering, which is glued or otherwise 45 suitably cemented to the leather *b*. This forms a strong and yet a stiff pad, which may be worn comfortably and which is at the same time possessed of sufficient rigidity to insure firmly holding the eyeglasses in place. If desired, the side portions of the chamois-skin *d* 50 may be disposed to slightly lap the edges of the leather *b*.

In this specification and claim I use the term "chamois-skin" as meaning chamois-skin proper and any one of the group of soft animal-skins constituting commercial equivalents of or substitutes for chamois—such, for example, as some of the finer skins of goats—while by the term "leather" is meant those 60 tough and heavy animal-skins ordinarily known as "leather."

Various changes in the form, proportions, and minor details of my invention may be resorted to at will without departing from the 65 spirit and scope thereof. Hence I consider myself entitled to all such variations as may lie within the intent of my claim.

Having thus described my invention, I claim as new and desire to secure by Letters Patent— 70

The combination with a metal eyeglass-guard, of a section of leather, a fastening means extending between the guard and leather to hold the leather in place, and a section of chamois-skin glued or cemented to the leather. 75

In testimony whereof I have signed my name to this specification in the presence of two subscribing witnesses.

WILLIAM H. WILSON.
